UNITED STATES PATENT OFFICE.

EINAR PEDERSEN, OF COPENHAGEN, DENMARK.

HAIR-PIN.

1,309,334.

Specification of Letters Patent.

Patented July 8, 1919.

Application filed April 12, 1918. Serial No. 228,162.

To all whom it may concern:

Be it known that I, EINAR PEDERSEN, of Copenhagen, Denmark, residing at No. 51 Gammel Kongevej, have invented certain new and useful Improvements in Hair-Pins, of which the following is a specification.

My invention concerns a hairpin, the special form of which prevents it from dropping out.

10 For the secure fastening of the hairpin various other forms of the legs of the hairpin have formerly been proposed.

The disadvantages of the hairpins, known hitherto, are that they are rather expensive 15 to make, and they are very apt to dishevel the hair.

Whereas the present invention concerns a special form of the legs, by which the pin, after having been put in, will be unable to 20 drop out. The advantages of the present invention are that the making of the pin is not more expensive than that of the usual straight ones, and it will not dishevel the hair.

25 The invention is shown on the drawing representing a hairpin seen from the side.

On the drawing the legs of the pin are marked 1 and 2.

The characteristic feature of the invention consists in both legs being curved; but in 30 order to attain the legs' preventing each other from displacing through a movement of the hair, the two legs are curved with different radii of curvature.

If for instance leg 1 begins slipping, leg 35 2, being curved according to a curve having a lesser radius of curvature, will oppose this movement of leg 1, and vice-versa leg 1 will oppose any movement of leg 2.

Having now described my invention what 40 I claim is new and desire to secure by Letters Patent is:

A hairpin comprising a single smooth piece of material, having a bight and two legs, said legs lying in a common plane and 45 being of different curvatures.

In testimony whereof I affix my signature in presence of two witnesses.

EINAR PEDERSEN.

Witnesses:

C. MARTENS,
CHARLES HUDE.
